BUILDING CONSTRUCTION

Richard M. Nyhagen, Jr., Chicago, Ill.

Application February 24, 1940, Serial No. 320,627

3 Claims. (Cl. 72—106)

This invention relates to building construction including walls comprising structural units of stone, terra cotta, granite, marble or other materials susceptible of being damaged or ruptured by excess pressure or weight, and to means for preventing such destruction.

Among the objects of my invention is to provide a filler or joint that not only compresses when a given load is imposed upon it, but also is adapted to return toward or to its original position when the load is lessened or diminished. The ability of my device to expand, spring back or return to or toward its original position is based on its own strength in relation to the added or decreased weight imposed or lessened. This is accomplished by designing this device to sustain a certain weight, to break down when that weight is exceeded and to expand or push back toward its original position when the excess weight is diminished or lessened.

An advantage obtained from my device is to regulate the maximum load to be imposed on the above mentioned structural units and to insure that the imposed weight will not exceed a given capacity. Also, when this excess weight is released, as in the case of these structural units having expanded due to temperature changes and imposing an excess weight on these units and then a contraction due to opposite temperature changes causing this weight to be released, my device will have the ability to force this structural unit to the point of maintaining the desired, intended weight. Consequently, when the lightening of the weight on these units becomes sufficient that there is a possibility of that undesirable feature, a loose or open joint, my device will possess sufficient strength to expand, thereby maintaining a watertight course and compensation for the movement resulting from contraction as well as having allowed for previous movement which resulted from the expansion of the facing units. As an example, we will presume that my device is designed to carry a load of 100 pounds per square inch. The structural units have been saddled with an excessive load due to various unavoidable and ever-present movements. My device will compress to that point where this excess pressure has been lessened to 100 pounds per square inch on the structural units. The next movement, we will assume, creates a contraction in the structural units which causes the load to lessen to the point where there is not enough weight to create a tight bond, which will result in an open course or joint. In this condition my invention pre-

sents enough strength to force itself to thicken, thereby returning the desired 100 pound per square inch weight to the structural units.

Referring to the drawing, Fig. 1 is a perspective view of my compressible and expandable filler; Fig. 2 is a sectional view of the device shown in Fig. 1; Fig. 3 is a sectional view of a wall with my filler therein; Figs. 4 and 5 are sectional views of different embodiments of my filler.

The embodiment selected to illustrate my invention in Figs. 1, 2 and 3 comprises a compressible and expandable body member 10 having a plurality of angular sections 11 formed by upwardly inclined portions 12 extending to peaks 13 and continuing on the other side as downwardly inclined portions 14 to valleys 15. An envelope or cover 16 is formed of such a size as to substantially inclose the body member 10 and to leave a space 17 to receive the body member 10 whenever the body member is compressed.

In Fig. 3 a wall 18 is shown with an embedded bolt 19 supporting an angle iron 20, and facing units or blocks 21, 22 and 23, and mortar, mastic or other filling 24.

The body member 10 is made of sheet metal, metal alloys, rubber or similar elastic material of sufficient strength to carry a definite weight and break down at a given point, and also having sufficient spring or elastic strength to return to or toward its original position when that weight is lessened or released. The cover or envelope 16 is for the purpose of added insurance against any possible moisture at this level due to the irregular profile of the body member. Also, the cover is to insure a uniform bearing on which the body member may ride. The cover is made of metal, metal alloy or other such material of equal or less strength than the body member 10 and is capable of resisting the attacks of the elements. The space 17 is advantageous although not absolutely necessary in that it affords room to receive the body member 10 and directs its movement when it is crushed down or compressed. The preferable location for this space is to enable the body member to move toward the rear or away from the face of the structural units. In Fig. 3 my filler is shown at some point above or below the shelf angle 20. This is not necessary and is only for convenience. The shelf angle 20 is anchored onto the weight-carrying column 18. This is a usual form of construction. The purpose is for this shelf angle to transfer the weight of the facing units onto the weight-

carrying columns at each floor or wherever these shelf angles are placed.

The facing unit 21 cannot always rest on the shelf angle as intended due to the compression of steel, expansion of stone, faulty setting and other causes. Thus the weight of facing unit 21 together with the weight of the above facing units are thrust upon facing unit 22 which is transferred to the lower facing units, and so on down. At this point my filler is crushed to the point of 10 permitting facing unit 21 to rest on the shelf angle 20 which transfers the weight to structural member 18. The condition of expansion of the stone which has contributed to the excess pressure is subject to contraction when the next reverse temperature change occurs. Existing structures make no allowance for this contractive movement. At this point, when the facing units contract, my invention will maintain the weight 15 in the wall by forcing itself toward its original position. If this is not done the facing unit 21 will remain on the shelf angle 20 while facing unit 22 will draw away from facing unit 21. This condition will be repeated at each shelf angle. This must occur as the colder temperature has 20 created a shorter distance from facing unit 22 above or below than that distance between shelf angle 20 and the corresponding shelf angle above or below.

In Fig. 4 a slightly different embodiment of my 30 invention discloses a body portion 10 with a plurality of sections 11 formed by upwardly inclined portions 12 extending to peaks 13 and continuing on the other side as downwardly inclined portions 14 to valleys 15. At the end of one of the valleys 15 I continue integrally with the body portion 10 to form a bent back portion 25. This eliminates the need of a separate cover or envelope 16.

In Fig. 5 my filler is shown as the body portion as heretofore described for use in the building construction without a cover 16.

This invention is not confined to the above described type of construction, but also where the facing units are anchored or bonded onto the floor as well as in wall bearing structures. While I prefer to construct my joint of a type of spring steel, steel alloys, fiber, rubber, metal or the like, yet it is within the spirit of my invention to construct my joint of any compressible material with sufficient strength to return to its original position after it has been compressed. The preferred shape of the body member as shown in Fig. 2 is of peaks and valleys. However any series of raised portions may be used such as a single concave or convex distortion, a plurality of concave or convex distortions, multiple or individual springs, tubes, cones, pyramids or angles. The direction or placing of the above described shapes and forms may be spaced and inter-spaced so often or seldom as desired and in any direction in relation to the face.

The ends of the envelope 16 need not meet as shown in Fig. 1. The extent of this envelope 65 may cover the body member 10 in entirety or in part.

Also, the body member 10 may be used by itself without the cover as shown in Fig. 5. In the event the body member 10 is used alone it would be desirable to recess the same from the face of the structural units and insert a sufficient amount of waterproofing compound to insure a water-tight course. Also, as shown in Fig. 4 the body member may be continued so as to pro-

duce a distortion with a plain border 25 to be folded onto itself, so that the body member 10 and cover 25 constitute one piece before folding and a single unit after the piece has been folded onto itself. This form may be folded to be a border on one side or both sides with the distortion down the center, near the center or on one side. This form may be used as often as desired in any height.

By maintaining a constant, uniform weight throughout the various seasons and conditions and by centralizing the various movements at a given point, that is, the course at which my filler is placed, there should be no reason to ever have spalls or cracks due to expansion, contraction, compression, settlement, wind stress, faulty setting and other destructive movement. Also, the use of my invention eliminates practically all future tuck-pointing.

My invention contemplates such other objects, advantages and capabilities as are inherently possessed by my invention. While I have shown and described herein preferred embodiments of my invention, yet I wish it understood 25 that the same are susceptible of modification and change without departing from the spirit of my invention.

Having thus described my invention, I claim:

1. In a building construction having a wall, a plurality of vertically spaced shelf angles attached to said wall, a plurality of vertically arranged facing units between each shelf angle, the facing unit immediately above an adjacent shelf angle resting thereon, a plurality of cushion joints, each of said cushion joints comprising a body member of resilient material, said body member having a plurality of upwardly and downwardly extending portions forming spaced peaks and valleys, said cushion joints vertically spaced and positioned between said facing units and supporting the weight of the facing units thereabove, said cushion joints adapted to carry a known weight in normal position, to compress upon receipt of excess weight and to return toward and to normal position upon the lessening and removal of the excess weight thereon.

2. In a building construction having a wall, a plurality of vertically spaced shelf angles attached to said wall, a plurality of vertically arranged facing units between each shelf angle, the facing unit immediately above an adjacent shelf angle resting thereon, a plurality of cushion joints, each of said cushion joints comprising a body member of resilient material, said body member having a plurality of upwardly and downwardly extending portions forming spaced peaks and valleys, an envelope inclosing said body member, said envelope of material less resilient than said body member, said envelope having space to receive the body member in compressed position, said cushion joints vertically spaced and positioned between said facing units and supporting the weight of the facing units thereabove, said cushion joints adapted to carry a known weight in normal position, to compress upon receipt of excess weight, and to return toward and to normal position upon the lessening and removal of the excess weight thereon.

3. In a building construction having a wall, a plurality of vertically spaced shelf angles attached to said wall, a plurality of vertically arranged facing units between each shelf angle, the facing unit immediately above an adjacent shelf angle resting thereon, a plurality of cushion

ion joints, each of said cushion joints comprising a body member of resilient material, said body member having a plurality of upwardly and downwardly extending portions forming spaced peaks and valleys, said body member bent back on itself to form a substantially straight cover portion, said cushion joints vertically spaced and positioned between said facing units and sup-

porting the weight of the facing units thereabove, said cushion joints adapted to carry a known weight in normal position, to compress upon receipt of excess weight, and to return toward and to normal position upon the lessening and removal of the excess weight thereon.
